UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed May 8, 1922. Serial No. 559,227.

To all whom it may concern:

Be it known that I, CHARLES DAVID BONSALL, a citizen of the United States, and a resident of the city of Pittsburgh, county 5 of Allegheny, and State of Pennsylvania, have invented a new and useful Improvement in Car Roofs, for which the following is a specification.

This invention relates principally to car 10 roofs of the all-steel riveted-up type wherein metal roof sheets extend from eaves to eaves of the car and are rigidly secured thereto and to each other to form a load sustaining structure. One of the principal objects of 15 the present invention is to increase the strength and rigidity of the roof by improving the sectional shape of the roof sheets. Another object of the invention is to simplify the operation of pressing the roof sheets. 20 Other objects are to reduce the weight of the roof, to simplify the construction thereof and to reduce the cost of manufacture.

The invention consists principally in stiffening the roof sheets by means of a succession of raised offsets, whereby said sheets are adapted to carry a considerable vertical load and are capable of offering considerable resistance to the stresses that tend to distort the car-frame. The invention also consists in the parts and in the arrangements and combinations of parts hereinafter described and claimed.

In the accompanying drawing, which forms part of this specification and wherein like symbols refer to like parts wherever they occur,

Fig. 1 is a plan view of a portion of a car roof embodying my invention;

Fig. 2 is an enlarged longitudinal section 40 along the ridge line of the roof on the line 2-2 in Fig. 1;

Fig. 3 is a transverse section through one-half of the roof on the line 3-3 in Fig. 1; and

Fig. 4 is a section similar to Fig. 3 showing a modified form of roof.

The present roof comprises heavy gage roof sheets 5, which are arranged crosswise of the car and slope upwardly from the 50 eaves to the ridge. The roof sheets are supported at their eaves ends on the uppermost flanges of angle-bar side plates 6 and are rigidly secured thereto by means of rivets 7. The eaves ends of the roof sheets are preferably provided with depending flanges 8

that overhang the outer margins of the side plates and constitute drip flanges. The roof sheets have their side margins overlapped and rigidly secured together by rivets 9 to form lap-seams or joints.

Running boards 10 are arranged lengthwise of the car at the ridge and are securely bolted to the uppermost lateral flanges of Z-shaped running board saddles 11, whose lowermost lateral flanges rest on the overlapped side marginal portions of the roof sheets and are rigidly secured thereto by the rivets 9 that rigidly secure together said overlapped margins.

The roof sheets are stiffened, both transversely and longitudinally of the roof by means of a series of raised offsets A, B, C and D. The surfaces of the offset portions are of corresponding width and are offset both vertically and horizontally with relation to each other, the highest surface D being located at the middle of the sheet and extending parallel with the side margins thereof and the lowermost surface being continuous and forming the side and end margins of the sheet. The succession of raised surfaces A, B and C extend continuously around the sheet, parallel with the side and end margins thereof, and are arranged one behind and above the other from the margins of the sheets to the raised middle portion D thereof, thereby forming an even series of steps along all four sides of the sheets after the manner of a stepped pyramid.

The above described roof has many advantages. In the first place, the sheets, by reason of the even series of continuous shallow steps formed therein, are well adapted to be pressed in a single operation of the press and without injury to the metal. In the next place, the sheets are not only designed so that a light weight of metal will carry the vertical load, but are especially well adapted to offer resistance to the horizontal stresses that tend to distort the car-frame and thus buckle the sheets. It may be noted that the sectional shape of the sheets permits stacking or nesting of the sheets one on another and thus economizing space and minimizing the danger of damaging the sheets in shipping.

In the modified construction shown in Fig. 4, the continuous steps are of gradually decreased depth from ridge to eaves. This

arrangement forms a stepped sheet whose depth is greatest at the ridge, whereby the sheet is adapted to withstand a considerable vertical load in this region.

5 Obviously, my invention admits of considerable modification without departing from the invention and I do not wish to be limited to the form of roof joints shown.

What I claim is:

10 1. A car roof comprising a series of metal roof sheets connected together and to the car-frame, each of said sheets comprising a raised middle portion and a series of rectangular steps extending from the margins 15 of said sheet to the raised middle portion thereof.

20 2. A car roof comprising a series of metal roof sheets connected together and to the car-frame, each of said sheets comprising a raised middle portion and a series of continuous steps extending from the margins of said sheet to the raised middle portion thereof, the portions of said steps that extend transversely of the roof being deepest 25 at the ridge and gradually decreasing in depth towards the eaves.

30 3. A car roof comprising a series of metal roof sheets connected together and to the car-frame, said sheets having substantially the shape of a rectangular stepped pyramid.

4. A car roof comprising a series of metal roof sheets connected together and to the car-frame, said sheets being substantially the shape of a stepped pyramid, whose steps 35 are deepest at the ridge and decrease in depth towards the eaves.

5. A car roof comprising a plurality of rectangular roof sheets extending from side plate to side plate and rigidly connected 40 thereto and to each other, each of said roof sheets comprising a raised middle portion and a succession of continuous rectangular steps extending from the four

margins of the sheet to the raised middle portion thereof.

6. A car roof comprising a plurality of metal roof sheets extending from side plate to side plate and rigidly connected thereto and to each other by lap-joints, each of said sheets comprising an offset middle portion and a continuous series of rectangular steps extending from the opposite margins of said sheet to the offset middle portion thereof.

7. A car roof comprising a series of metal roof sheets connected together and to the car-frame, each of said sheets comprising an offset middle portion and a continuous series of rectangular steps extending from the margins of said sheet to the offset middle portion thereof.

8. A car roof sheet comprising an offset middle portion and a series of rectangular steps extending from the margins of said sheet to the offset middle portion thereof.

9. A car roof sheet comprising a raised middle portion and a series of steps between and parallel with the margins of said sheet and the raised middle portion thereof.

10. A car roof sheet comprising raised 70 middle portions and a series of steps between the margins of said sheet and the raised middle portion thereof, said steps being deepest at the ridge and decreasing in depth on opposite sides thereof.

75 11. A car roof sheet having substantially the shape of a rectangularly stepped pyramid.

12. A car roof sheet having substantially the shape of a stepped pyramid, the portions 80 of the steps extending lengthwise of the sheet being deepest at the ridge and decreasing in depth towards the eaves.

Signed at New Kensington, Pa., this 4 day of May, 1922.

CHARLES DAVID BONSALL.
